Application March 12, 1941, Serial No. 382,895

6 Claims. (Cl. 235—135)

The present invention relates to registering or counting apparatus and has particular relation to a mechanism for registering the total amount or number of units of material dispensed and means for simultaneously registering the total cost of the material dispensed.

In the present instance, the mechanism is shown as being adapted for use with apparatus for dispensing gasoline or other fluids and wherein it is desired to simultaneously register both the amount dispensed and the cost thereof.

An object of the present invention is to provide in an apparatus of the above-indicated type an improved transfer mechanism whereby the step by step advance of the wheels of higher order is controlled through means driven from and in direct relation to the wheel of lowest order and where such transfer means include means for preventing an overthrow of the numeral wheels during a counting operation.

A further object is to provide in a mechanism of the above-indicated type an improved drive unit for operating the lowest order wheels, the higher order wheels, and for releasing the means for preventing overthrow of the numeral wheels of higher order; said drive unit being so constructed as to carry out the aforementioned operations in timed relation to one another.

Another object is the provision in an apparatus of this type of improved means for controlling and operating the transfer mechanism and wherein the operation of the transfer mechanism between the wheels of lower order and the wheels of higher order is operated from and through the drive means for the wheels of lower order.

A still further object is to provide an improved registering or counting mechanism of the above-indicated type including resetting mechanism and wherein the resetting mechanism operates to release the counters from the drive and transfer means and thereafter reset them to zero.

A still further object is to provide an improved registering or counting mechanism of the above-indicated type which is characterized by its compactness in arrangement, simplicity in operation, economy in manufacture, and dependability in service and performance.

Other objects will be in part obvious and in part pointed out more in detail hereinafter.

The invention accordingly consists in the features of construction, combination of elements, and arrangement of parts which will be exemplified in the construction hereinafter set forth and

the scope of the application of which will be indicated in the appended claims.

In the accompanying drawings:

Figure 1 is an elevational view of the registering mechanism embodying the invention herein;

Fig. 2 is a plan view of the apparatus shown in Fig. 1;

Fig. 3 is an elevational view through the center line of Fig. 1;

Fig. 4 is a more or less diagrammatic perspective view of one of the counter wheels showing the transfer mechanism;

Fig. 5 is an end view with the front supporting plate removed to show the transfer mechanism with the parts in position immediately following a transfer;

Fig. 6 is a view similar to Fig. 4, but with the transfer mechanism released to permit a resetting operation;

Fig. 7 is a perspective view of one of the counter wheels showing the reset element of the transfer mechanism;

Fig. 8 is a sectional view through one of the counters to show the details of construction and the mounting of the counters on the supporting shafts;

Fig. 9 is a view showing the means operative during resetting for clutching the counter wheels to their supporting shafts;

Fig. 10 is an end view showing the means for disconnecting the counters from the drive means;

Fig. 11 is a front view of the member for operating the means for conditioning the numeral wheels for a resetting operation; and

Fig. 12 is a modified view of the drive unit.

Referring to the drawings, the mechanism includes generally four counters designated as A, B, C, and D, which, together with the mechanism for operating same, are supported between a front frame plate 10 and a rear frame plate 12. The plates 10 and 12 are stamped from any suitable metal and interconnected by bracing members 14 to hold the mechanism as a compact unit.

More particularly, the four counters are of like construction, and referring specifically to the counter A (see Fig. 8), it includes a numeral wheel 16a of lowest order, a second numeral wheel 18a of intermediate order, and a third numeral wheel 20a of highest order. Each

numeral wheel comprises a hub 22, a discoidal web 24 extending radially from one end of the hub, and a rim 26 extending from the web in the same direction as and paralleling the hub 22. In the embodiment illustrated, the rims 26 of the numeral wheels of the counters A and B

carry indicia from 0 to 9 to indicate the cost of the material dispensed; the wheel 16a designating units, the wheel 18a designating tens, and the wheel 20a designating hundreds. As the counters C and D are used to designate the amount of material dispensed, the indicia on the rims 26 of these numeral wheels differs only in that the wheels successively indicate tenths, units, and tens.

The lowest order wheel 16a is further provided with a driving gear 28a which is shown as formed integral therewith, but obviously could be an independent gear secured in any suitable way to the wheel. The successively higher order wheels differ from the lowest order wheel in that they carry a transfer ratchet; that associated with the second numeral wheel being designated as 30a and that with the third wheel as 32a; these ratchets being hereinafter fully described in connection with the drive mechanism. The order wheels of the counter A are supported and loosely rotatable on a counter shaft 34a, which shaft in turn is rotatably mounted in the frame plates 10 and 12 for reasons hereinafter apparent.

As all of the counters are of like construction to the counter A (except when otherwise noted), no further description thereof will be made as the corresponding parts have been given similar numbers with a small letter suffix corresponding to the capital letter designating the counter.

In order to arrange the counters so that a cost and amount counter may be seen through windows in each side of the usual casing (not shown) in which the device is mounted, the counter shafts 34a and 34b are arranged in spaced alignment in an upper horizontal plane, and the shafts 34c and 34d are arranged in spaced alignment in a lower horizontal plane and respectively in vertical alignment with the shafts 34a and 34b.

With the counters so located, there is provided a drive means for each pair, said means including an upper drive shaft 36 rotatably mounted in the frame members and located in horizontal alignment and midway between the cost counter shafts, and a lower drive shaft 38 similarly arranged relative to the material counter shafts. The upper drive shaft 36 is connected to a variator (not shown) through a driving connection including a beveled gear 40 secured on shaft 36 and meshing with a bevel gear 42 secured to the upper end of a connecting shaft 44. The lower end of the shaft 44 carries a second bevel gear 46 meshing with a bevel gear 48 rotatably mounted on a stub shaft 50; the bevel gear 48 meshing with a crown gear 52 operatively connected to the variator in any suitable way. In like manner, the lower drive shaft 38 is connected to a meter (not shown) through a driving connection including a gear 53 secured to shaft 38 and meshing with a gear 54 secured to a shaft 56 rotatably mounted in the frame members. There is also secured on shaft 56 a bevel gear 58 meshing with a bevel gear 60 secured to the upper end of a shaft 62 operatively connected in any suitable way to the meter.

In this manner, upon a dispensing operation being carried out, the drive shafts 36 and 38 will be rotated, and means are provided for transferring their rotation to the respective counters associated therewith. As the means for accomplishing this transfer are duplicated, the description of these parts (except where otherwise indicated) will relate to the cost counter drive means, and like numerals will be applied to like

parts of the material counters drive means, except that the numerals associated with the material counters are primed.

To accomplish the transfer of rotation from the drive shaft to the cost counters, there is rotatably mounted on shaft 36 a drive unit generally designated as 37 and adapted for controlling the operation of the order wheels of the adjacent counters. More specifically, the drive unit 37 includes an elongated sleeve 64 having secured to its forward end a drive gear 66 and to its after end a second drive gear 68. As best seen in Fig. 2, the spacing between the gears 66 and 68 is such that the gear 66 meshes directly with the drive gear 28a of the lowest order wheel of the counter A and the gear 68 meshes directly with the drive gear 28b of the lowest order wheel of the cost counter B. In this way, upon rotation of the gears 66 and 68 in a counterclockwise direction (as viewed in Figs. 1 and 4), the lowest order wheels of the opposed cost counters will be simultaneously rotated in a clockwise or counting direction.

To connect the gear-carrying sleeve 64 to the drive shaft 36, there is provided a cone clutch, generally designated as 70, including a female clutch member 72 formed on the forward face of the drive gear 66 and a male clutch member 74 secured to a sleeve 76 slidably mounted on the shaft 36. In order to rotate the sleeve 76, the latter is provided with a flange 88 radially spaced from the sleeve by a web 89; the flange 88 being provided with splines receivable within slots provided in a throat 90 formed in the drive gear 40. The clutch members 72 and 74 are normally urged to the driving position shown in Fig. 3 by a spiral spring 82 having one end seated within a recess 86 provided in the hub of the drive gear 40 and its other end abutting the web 89 of the sleeve.

In the present instance, the drive gear 66 not only operates the lowest order wheel of the counter A, but also carries means for operating the transfer means for making a step by step advancement of the higher order wheels of both cost counters A and B upon predetermined rotation of the lowest order wheel of the counter A. To accomplish this transfer, there is formed integral on the after face of gear 66 a positive motion cam 91 having a track (see Figs. 3 and 4) in which there rides a cam follower 94. Operated by the cam 91 is a bell crank transfer lever 96 having a vertical arm 98 and a horizontal arm 100 carrying at its outer end the cam follower 94; the lever 96 being pivotally mounted at the juncture of the arms on a control shaft 102 rotatably mounted in the frame members. To operate the lever 96 the track cam 92 includes an advancing portion 104 which is so located relative to the lowest order wheel that when the numeral 9 is aligned with the pointer 93 the follower 94 will enter the track portion 104 where upon continued rotation the transfer lever 96 will be pivoted in a clockwise direction until the numeral 9 is aligned with the pointer 93, at which point the follower 94 will have reached the end of the portion 104. The remainder of the track 92 is so formed that upon continued rotation the transfer lever 96 will be slowly pivoted in a counterclockwise direction; this alternate pivoting of the transfer lever being utilized for advancing the higher order wheels.

To transfer the movement of the transfer lever to the higher order wheels, there is provided means, generally designated by the numeral 106, for advancing the higher order wheels of the

counter A and means, generally designated as 108, for advancing the higher order wheels of the counter B. Referring initially to the means 108, it includes a link 110 pivotally connected at one end to the vertical arm 98 of the transfer lever 96 and at its other end to the upper end of a vertical lever 112, which lever is pivotally mounted at its lower end on an auxiliary shaft 114 supported between the frame members. Also pivoted on the upper end of the lever 112 is a transversely extending transfer arm 116 carrying on its outer end (left, as viewed in Fig. 4) a long depending pawl 118a and a short depending pawl 120a. These pawls are so spaced that pawl 118a engages the ratchet 30a of the intermediate numeral wheel 18a and the pawl 120a engages the ratchet 32a of the highest order wheel 20a.

The engagement of the short pawl 120a with the ratchet 32a is controlled by the movement of the ratchet 30a; this latter ratchet being provided with nine shallow notches 121a and one deep tooth notch 122a. The deep notch 122a is so positioned on the ratchet that the drive pawl will be received therein when the numeral 9 of the intermediate wheel is aligned with the indicator 93 whereby upon the next operation of the transfer means both the intermediate wheel and the highest order wheel will be advanced one step. With this construction, when the long pawl 118a is positioned in any of the nine shallow notches of the ratchet 30a, the short pawl 120a will be raised above the peripheral edge of the ratchet 32a, whereas when the long pawl is positioned in the deep notch 122a, the short pawl 120 will be engaged in one of the notches of the ratchet 32a; these notches all corresponding in depth to the shallow notches of ratchet 32.

In the embodiment illustrated, the driving pawls 118a and 120a and the ratchet teeth of the ratchets 30a and 32a cooperate to prevent overthrow of the numeral wheels when the latter are advanced in a counting direction. To accomplish this, the ratchet pawls and notches are cut substantially rectangular whereby when they are received in one of the notches they cannot be removed therefrom except by pivoting the transfer arm to raise the pawls vertically until they clear the periphery of the ratchets. In this way, once the pawls are positioned within the notches there is a positive interlock therebetween, and if a numeral wheel should tend to overthrow, the next succeeding tooth will engage the driving pawl and restrain further movement of the wheel.

In order to release the pawls 118a and 120a from the ratchet teeth, there is carried by the drive gear 68 a releasing means comprising a cam 126a positioned in timed relation to the advance of the numeral wheels so that it will engage the under surface of the transfer arm 116a shortly after the completion of an advance of the numeral wheel and pivot the transfer arm upwardly to lift the drive pawls from the ratchet notches. The cam 126a is of such length that it will retain the transfer arm 116a in its raised position until the transfer lever 98 has moved sufficiently in a counterclockwise direction to move the transfer pawls out of alignment with the ratchet tooth notch from which it has been lifted. When the pawl has been moved out of alignment with the notch from which it was released, the cam 126a will then move out of engagement with the transfer arm 116a, permitting the transfer arm to lower until the pawl engages the next succeeding tooth, whereupon continued movement of the transfer arm the pawl will align with and drop

into the next succeeding notch. Obviously the cam 126a could be so constructed that the transfer arm is maintained out of engagement with the ratchet from the time the drive pawl is released from one notch until it is aligned with the next successive notch.

Referring now to the means 108 for advancing the higher order wheels of the counter B, this means includes a transfer arm 116b pivoted at its inner end to the upper end of the vertical arm 98 of the transfer lever 96 and carrying at its outer end transfer pawls 118b and 120b respectively engaging the ratchets 30b and 32b; the transfer arms 116b and pawls 118b and 120b carried thereby being of similar construction to the transfer arm 116a and pawls 118a and 120a. In order to release the pawls 118b and 120b from their respective ratchets, the drive gear 68 carries a cam 126b of like construction to the cam 126a and located in a like relative position whereby it controls the transfer arm 116b in the manner cam 126a controls the transfer arm 116a.

It will also be noted that inasmuch as the lowest order wheels are operated in the same direction, the transfer arms 116a and 116b must likewise operate the higher order wheels in the same direction. For this reason, the transfer arm 116a in effect pulls the higher order wheels of the counter A, whereas the transfer arm 116b pushes the higher order wheels of the counter B.

In order to prevent reverse rotation of the order wheels following an advance in the counting direction, there is associated with each of the ratchets of the wheels of higher order a retainer or non-back-up pawl 132; those associated with the counter A being pivotally mounted intermediate of their ends on the control shaft 102 and those associated with the other counters being pivotally mounted on the auxiliary shafts 114. Each of the pawls 132 terminates at its upper end in a nose 136 adapted to be received within a ratchet notch to thus restrain the wheels against reverse direction. In order to so position the pawls, they are normally pivoted into engagement with the ratchets by means of a spring 140 which is secured at its lower end to the pawl supporting shaft and at its upper end engages the side of the pawl remote from the ratchet with which the pawl is associated. Obviously, with this construction the pawls will normally be biased towards engagement with the ratchets, and when the wheels are operated in a counting direction the pawls will be pivoted out of engagement against the tension of the springs 140 until the pawl is aligned with the next succeeding notch, whereupon the spring will automatically urge it therein.

From the foregoing it will be seen that the drive unit 37 carried on the drive shaft for each set of counters simultaneously controls the driving operation of the lowest order wheels of the two counters and, through the positive cam 92, also controls the complete drive for all of the order wheels of both of the opposed counters. In addition to the foregoing, this drive means also includes the releasing cams 126 whereby the transfer arms may be released from the respective ratchets following a transfer thereof, thus breaking the interlocking engagement, whereby the overthrow of the wheels is prevented. By incorporating all of the foregoing structures into the single unit, it is obvious that they may be arranged in such order that all of the foregoing operations may be synchronized to operate in

proper timed relation to one another to accomplish the results desired. In addition, the foregoing structure lends itself to ready manufacture and quick assembly and, by utilizing a minimum number of parts, considerably reduces the cost of manufacture.

Referring now to the resetting means, there is provided a centrally located reset shaft 142 rotatably journaled in the frame members 10 and 12. Upon rotation of the reset shaft, it operates mechanism to break the clutching engagement between the counter drive shafts and the counters, to release the transfer pawls from the higher order wheels, release the retainer or non-back-up pawls from the order wheels, clutch the order wheels to the countershafts, and thereafter rotate the counter shafts to return the order wheels to zero position.

To accomplish these various steps, there is secured to the reset shaft forwardly of the frame 10 a reset cam 144 (see Figs. 1 and 2) having a peripheral notch 146 which, when the counters are in zero position, lags approximately 90° behind vertical position. Positioned in notch 146 during counting operations is a follower 148 carried on the outer end of a crank arm 150 secured to the control shaft 102. The crank arm is normally urged in a clockwise direction by a spring 152 connected at one end to the follower 148 and at the other to the extending end of a shaft 114; this rotation tending to rotate the reset cam 144 in a counterclockwise direction when the follower 148 is located within the notch 146.

To limit this rotation, there is struck from crank arm 150 a stop tab 156 engageable against a reset stop arm 158 of a bifurcated lever 160, which lever is pivoted intermediate of its ends on the control shaft 102. As indicated, when the stop tab 156 abuts the arm 158, the lever 160 will be pivoted in a clockwise direction until the opposite arm 162 of the lever 160 engages the periphery of a non-back-up ratchet 164 secured to the main reset shaft 148 rearwardly of the reset cam 144, thus limiting further rotation. The lever 160 is also urged to the position shown in Fig. 1 by a spring 166 secured at one end to the finger 158 and at the other to the frame member 10. However, upon rotation of the reset shaft, the control lever will be pivoted in a counterclockwise direction, and when the tooth 168 of the non-back-up ratchet 164 clears the end of the arm 162, the spring 166 will pivot the arm to locate it behind the tooth and thus prevent reverse rotation of the reset shaft. Thereafter, upon continued rotation of the reset shaft, the follower 148 will ride out and onto the periphery of the reset cam 144, rotating the control shaft 102 through approximately 45°.

It will also be noted that the lever 150 extends beyond the control lever 160, and there is associated therewith a latch 151 pivoted to the frame member 10 on a stud 153. The latch 151 includes a depending arm 155 and an upwardly extending arm 157, which arm is connected through a spring 159 to the frame member 10 whereby the latch is normally urged to rotate in a counterclockwise direction. To prevent such rotation, the depending arm carries at its lower end an outwardly turned shoulder 161 which normally abuts when the parts are in zero position against the end of the lever 150. However, when the lever 150 has been rotated through the 45° previously described, it will clear the shoulder 161 of the latch, whereupon the latter will be pivoted until it abuts against the end of lever 160.

When the reset shaft has been rotated sufficiently to cause the follower 148 to ride onto the periphery of the cam 144, the zero limiting notch 163 carried by the non-back-up ratchet will have moved to a position where it engages beneath the non-back-up arm 162 of the lever 160, whereupon it will pivot this lever counterclockwise against the tension of spring 166. When this occurs, the latching shoulder 161 of the latch 155 will then 10 move into the path of a shoulder 165 formed on the outer end of the lever 160 to restrain this lever in position. When so restrained, the arm 158 of the lever 160 will then lie in the path of rotation of the tooth 163 and thus restrain further rotation of the reset shaft. This restraint will occur when the notch 146 is again aligned with the follower 148, whereupon the spring 152 will cause the lever 150 to rotate in a clockwise direction and the reset shaft to rotate in a counterclockwise direction to return the parts to the positions indicated in Fig. 1. When this occurs, 20 the outer cammed edge 167 of the lever 150 will engage beneath the shoulder 161 of the latch 155, camming it outwardly to release the lever 160, whereupon this lever will be returned by a spring 168 to the position shown in Fig. 1.

Upon the rotation of the lever 150 to release the follower 148 from the notch 146, the control shaft 102 will simultaneously rotate a crank arm 170 (see Fig. 2), a gear segment 172, and a second gear segment 174, all fixed thereon. The crank arm 170 is provided at its outer end with a pin 176 receivable within the bifurcated end of a lever 178 (see Fig. 10) rotatably mounted on a collar 180 (see Fig. 3) secured to the reset shaft 142. The pivoted end of the lever 178 controls the movement of a yoke 182, which yoke is provided with opposite bifurcated ends 184 straddling the sleeves 78 of the counter clutch members 70 and 70', whereby when the yoke is moved longitudinally and to the right on the shaft 142 (as viewed in Fig. 3), the clutch members will be opened. To obtain this longitudinal movement, the pivoted end lever 178 is provided with forwardly extending detents 188 receivable within recesses 190 of the yoke member 182 when the parts are in driving relation. However, upon the pivoting of lever 178, the detents 188 will be rotated out of the recesses onto the flat face of 50 the yoke, moving it to the right, as seen in Fig. 3, and thus declutching the counters from their respective drive shafts.

Simultaneously with the foregoing operation the gear segment 172 is rotated, and this segment 55 meshes with a rack provided on an arm 191 extending laterally from a releasing member 192 (see Figs. 1 and 5) whereby the member 192 will be raised to release the transfer pawls and retainer pawls from engagement with the higher order wheels. As best seen in Figs. 2, 3, and 6, member 192 is mounted by cutting slots 194 therein through which the drive shafts 36 and 38 and reset shaft 142 extend; the length of the top and bottom slots acting to limit the vertical movement thereof. To guide member 192 in its vertical movement, the upper end may also extend through a slot 196 provided in one of the bracing members 14 extending between the frames 10 and 12.

In order to release the transfer arms upon upward movement of member 192, the latter carries forwardly and rearwardly extending fingers 200 so disposed that upon raising of the arm they will engage the transfer levers 108 and 106 to 70 pivot them out of contact with the ratchet wheels 75

as seen in Fig. 6. The raising of the member 196 also releases the non-back-up pawls 132, and for this purpose the slide carries transversely extending arms 202 of sufficient width to simultaneously engage the depending fingers 138 of the non-back-up pawls to pivot them out of the notches of the numeral wheel ratchets and free same for a reset operation.

To cooperate with the foregoing, the second gear segment 174 operated by the control shaft 102 simultaneously functions to shift a clutch operating member 205 transversely and to the right, as seen in Fig. 9, to clutch the order wheels of each counter to their respective supporting shafts. As best seen in Fig. 11, the member 205 comprises a substantially rectangular plate 206 provided with arms 208 extending laterally from the left-hand edge thereof and arms 210 extending laterally from the right-hand edge thereof. Each of the arms 208 and 210 are provided with a slot 212 through which the counter supporting shafts extend for mounting the slide for transverse movement on the supporting shafts. In order to operate the member 205, plate 206 has an opening 214, the lower edge of which is provided with teeth to form a rack 216 meshing with the gear segment 174.

Upon the transverse movement of the clutching member 205, detents 218 provided on each of the arms 210 will be moved into alignment with the respective counter supporting shafts whereby the numeral wheels will be shifted longitudinally and to the right on the supporting shafts (as viewed in Fig. 8); this longitudinal movement being limited by a stop 240 abutting the hub of the lowest order wheel. When this longitudinal movement occurs, the wheels are clutched to the supporting shafts by friction means whereby upon rotation of the shafts the wheels will rotate simultaneously therewith.

Referring again to Fig. 8, the friction clutching means comprises a friction member 220 non-rotatably slidably secured on the shaft 34a by a depending tongue 222 extending into a groove 224 provided in the shaft and positioned between the arm 208 of the clutching member and the adjacent end of the hub 22 of the highest order wheel. Upon the detents 218 being moved behind the friction member 220, the latter will be forced to the right, sliding the highest order wheel 20a to the right and into frictional engagement with a second friction member 226. This friction member is also nonrotatably but slidably secured to the shaft 34a in like manner to the friction member 220, but comprises a substantially large circular plate located between opposed friction faces 228 fixed to and extending outwardly from the discoidal webs 24 of the numeral wheels.

Obviously when the numeral wheel 20a is slid to the right and into engagement with the friction member 226, the latter will also be forced into engagement with the wheel 18a, whereupon the wheel 18a will be slid to the right. The movement of the wheel 18a to the right is utilized to actuate means for clutching the lowest order wheel to the shaft 34a as well as for increasing the frictional engagement between the intermediate and higher order wheels and the friction disk 226 to positively assure the rotation of all of the wheels upon the rotation of the shaft 34a.

To obtain the foregoing result, there is slidably mounted on the hub 22 of the wheel 18a adjacent the lowest order wheel 16a a friction plate 234 which is normally urged outwardly against a

shoulder or restraining ring 236 by a spiral spring 230. The spring 230 is mounted on the hub 22 of the wheel 18a and is normally self-contained between the friction plate and a hub shoulder 232; the spring being preloaded to normally exert just sufficient pressure against the friction plate to maintain it positioned against the shoulder 236.

The friction plate 234 further includes a friction face 235 which is offset to lie in a plane to the right of the end of the hub of the order wheel 18a and adjacent a friction member 238 of like construction to the friction member 226, which friction member when urged to the right will abut the friction face 228 of the lowest order wheel 16a.

With the foregoing construction, when the order wheel 18a is urged to the right, the friction face 235 of the plate 234 will engage the friction disk 238, and the latter will engage the lowest order wheel 16a; this engagement occurring prior to the completion of the full extent of sliding movement of the higher order wheels whereby the shoulder 236 will move away from the friction plate and the spring 230 will be placed under increased compression. When the spring 230 is placed under increased compression, it will then exert a pressure in two directions—one to positively urge the friction plate 234 and friction disk 238 into engagement with the lowest order wheel and the other to positively urge the intermediate order wheel and the higher order wheel into positive engagement with the friction member 226, thus positively assuring a rotation of all of the order wheels upon rotation of the supporting shaft 34a.

In addition to assuring a positive rotation of the numeral wheels, the utilization of the spring 230 reduces to a minimum the amount of sliding movement required to obtain frictional engagement between the wheels and friction member; in actual practice it being found that a clearance of a few thousandths of an inch is all that is required to permit free rotation of the wheels 45 when operating in a counting direction and to positively assure clutching when the wheels are moved longitudinally for a resetting operation.

In order to rotate the shaft 34a to reset position, the main reset shaft 142 carries a reset gear operating pawl 242 which, when the aforescribed operations have been completed, engages a lug 244 on a main reset gear 246. The main reset gear 246 meshes with four reset wheels 256; each being respectively secured to one of the counter shafts 34. In this manner, upon rotation of the main gear 246, the shafts 34 will all be simultaneously rotated in a counterclockwise direction and, when the wheels are clutched thereto, will simultaneously rotate the wheels in a like direction towards zero position.

In order to positively stop the wheels at zero position, the non-back-up pawls 132 also function as stop pawls, and to cooperate therewith each of the ratchets of the higher order wheels is provided with a stop lug 258 (see Figs. 4 and 6) extending radially from one of the ratchet teeth. The stop lugs 258 are approximately half the width of the teeth, whereby they will ride past the driving pawls during counting and resetting operations. It will also be noted that they extend radially a sufficient distance to contact the retainer pawls when the latter have been moved out of engagement with the ratchet wheel notches when the counter is conditioned for resetting (see Fig. 6). Due to the fact that the

wheels are only frictionally engaged to their respective shafts, the stopping of one wheel at zero does not interfere with the continued rotation of the others.

To positively stop the lowest order wheels at zero position, there is also associated with each of said wheels a non-back-up pawl 259 of like construction to the non-back-up pawls previously described. To cooperate with these pawls, the zero wheel is provided with a ratchet 261 having a single tooth 263, which tooth functions as a stop lug when the lowest order wheel is operated in reset direction to engage with the pawl and positively stop it at zero.

When the counters have all been reset to zero position, the notch 146 in the reset cam 144 will again align with the follower 148 whereby upon releasing the reset shaft 142 the spring 152 will again operate the crank arm 150 in a clockwise direction to return the reset cam 144 to the position shown in Fig. 1 and to simultaneously lower the slide 192 to re-position the transfer arms 108 and 108 and non-back-up pawls 132 and to operate the slide 205 transversely to declutch the wheels from their supporting shaft drive clutches and likewise to reverse the operation of the pawl 242 to move it out of contact with the main reset gear lug 244 and thus recondition the counter for a new counting operation.

It will also be noted, by reference to the reset stop pawl 163 (Fig. 1), that the reset shaft is operated through one complete revolution plus an overtravel; this overtravel being sufficient to assure that all of the wheels will be positively returned to zero position, thus compensating for any possibility of slip during the clutching of the wheels to their respective supporting shafts.

Reviewing the structure for accomplishing the resetting, it will be seen that upon the operation of the reset shaft a single slide member is utilized for controlling the non-back-up and stop pawls of all of the wheels of higher order and a second single member is utilized for clutching the wheels of all of the counters to their respective supporting shafts to condition them for resetting; both of these members being operated from the single reset shaft.

Referring to Fig. 12, there is shown a modified form of driving means for each pair of counters and wherein the declutching of the drive unit from the drive shaft is accomplished through the clutch slide member 205 which conditions the numeral wheels of the counter for resetting. To accomplish the foregoing, the drive unit 39, which is of like construction to that shown in the other embodiment, is rotatably mounted on a sleeve 260 slidably mounted on a drive shaft 262. The sleeve 260 has integral with its forward end a male clutch member 264 which is normally urged into clutching engagement by a spiral spring 266 positioned on the hub of the clutch member and receivable within a recess provided in the hub of a driving gear 40. As in the previous embodiment, the gear 40 is operatively connected to the variator when associated with the cost counters and with the meter when associated with the amount counters. In order to rotate the male clutch member 264, it is connected to the shaft 262 by a pin 270 extending through the shaft and secured to a collar 272 mounted on the sleeve 260, which collar also functions as a positioning member for the drive unit 39.

It will also be noted that the sleeve 260 is provided with diametrically opposed, longitudi-

nal slots 274 through which the pin 270 extends; these slots permitting longitudinal movement of the sleeve relative to the shaft 262. As previously explained, the clutching member 264 is normally urged into clutching engagement, and as the sleeve is integral therewith, it will also be urged rearwardly, or to the left as viewed in Fig. 12, whereupon its after end will abut against a spacer 276, which spacer lies flush against the clutching member 205.

To release the clutch 264, the clutching member is further provided with a longitudinal slot 278 (see Fig. 11) through which the drive shaft 262 extends, whereby the clutching member may be slid transversely relative to the shaft. The clutching member is further provided with forwardly extending detents 280 so positioned that upon transverse movement of the clutching member the detents will move behind the spacer 276, thus sliding the sleeve 260 longitudinally to open the clutch and thus break the driving connection between the drive shaft and drive unit. With this construction, it will be seen that the clutching member 205 not only functions to condition all of the numeral wheels for a resetting operation, but also breaks the drive connection between the counters and the respective drive means therefor.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a counter, a lower order wheel and a higher order wheel, drive means for continuously operating the lower order wheel in a counting direction, pawl and ratchet means operated by the drive means for said lower order wheel for advancing the higher order wheel upon predetermined rotation of the lower order wheel, said pawl and ratchet drive means including cooperating parts interlockable upon operation of the ratchet drive means in a counting direction to prevent overthrow of said higher order wheel, and means driven in unison with the lower order wheel drive means for releasing said parts upon operation of the pawl in a non-counting direction.

2. In a counter having a lower order wheel and a higher order wheel, a gear connected to the lower order wheel, a notched ratchet connected to the higher order wheel, a drive unit including a gear meshing with the gear connected to the wheel of lower order for operating said wheel in a counting direction, a cam carried by said drive unit, a transfer lever oscillated by said cam, a transfer arm pivoted at one end to said transfer lever and carrying a pawl at its other end, said pawl being receivable within the notches of said ratchet and releasable therefrom only upon pivoting of the transfer arm, and means carried by said drive unit for pivoting said arm to release the pawl from the ratchet notch.

3. In a counter, a numeral wheel, a notched ratchet connected to the numeral wheel, a piv-

oted drive pawl engageable in said notches for operating said numeral wheel, said pawl being releasable from said notches only by movement of the drive pawl about its pivot, means for oscillating said drive pawl, and means driven in unison with said last-named means for moving the pawl about its pivot to release it from said ratchet notches upon the completion of an oscillation in a driving direction.

4. In a counter, a numeral wheel, a ratchet connected to said wheel so as to rotate therewith and having notches, an oscillatory and pivoted arm having a pawl engageable in said notches and pawl being generally square-cut for preventing overthrow of said wheel and ratchet when the same are operated in a counting direction, drive means for oscillating said arm to advance the wheel with a step by step movement, and means associated with said drive means and driven in unison therewith for moving the arm outwardly about its pivot to release the pawl thereof from the notches of the ratchet upon completion of an oscillation of the arm in a driving direction.

5. In a counter, a numeral wheel, a ratchet connected to said wheel so as to rotate therewith and having notches, an oscillatory and pivoted arm having a pawl engageable in said notches, said notches and pawl being generally square-cut for

5 preventing overthrow of said wheel and ratchet when the same are operated in a counting direction, a rotatable cam for oscillating said arm to advance the wheel with a step by step movement, and means connected to and driven in unison with said cam for moving the arm outwardly about its pivot to release the pawl thereof from the notches of the ratchet upon completion of an oscillation of the arm in a driving direction.

10 6. In a counter, a lower order wheel and a higher order wheel, drive means for continuously operating the lower order wheel in a counting direction, a ratchet connected to said wheel of higher order so as to rotate therewith and having notches, an oscillatory and pivoted arm having a pawl engageable in said notches, said notches and pawl being generally square-cut for preventing overthrow of said wheel and ratchet when the same are operated in a counting direction, means associated with said drive means for oscillating said arm to advance the wheel of higher order with a step movement upon predetermined rotation of the lower order wheel, and means driven in unison with said drive means for pivoting said arm to release the pawl thereof from the notches of the ratchet upon completion of an oscillation of the arm in a driving direction.

HARVEY N. BLISS.
